UNITED STATES PATENT OFFICE

ABRAHAM FRIEDMAN, OF LOS ANGELES, CALIFORNIA, ASSIGNOR TO EARL COHEN, DOING BUSINESS AS NOVELTY MANUFACTURING COMPANY, OF LOS ANGELES, CALIFORNIA

DESIGN FOR A TABLE

Application filed May 26, 1931. Serial No. 39,994. Term of patent 7 years.

To all whom it may concern:

Be it known that I, ABRAHAM FRIEDMAN, a citizen of the United States, residing in the city and county of Los Angeles, State of California, have invented a new, original, and ornamental Design for Table, of which the following is a specification, reference being had to the drawings accompanying this specification and forming a part thereof.

Fig. 1 is a plan view of the table, showing my new design; and

Fig. 2 is a perspective view thereof.

I claim:

The ornamental design for a table as shown.

ABRAHAM FRIEDMAN.
